(57) **CLAIM**

The ornamental design for a cosmetic bottle, as shown and described.

DESCRIPTION

FIG. 1 is a front and top perspective view of a cosmetic bottle, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front and bottom perspective view of the cosmetic bottle shown in an open position.

The broken lines in the figures illustrate portions of the cosmetic bottle that form no part of the claimed design.
